UNITED STATES PATENT OFFICE.

GEORGE H. TAYLOR, OF NEW YORK, N. Y., ASSIGNOR TO THE KURSHEEDT MANUFACTURING COMPANY, OF NEW YORK, N. Y., A CORPORATION OF NEW YORK.

DESIGN FOR TRIMMING.

SPECIFICATION forming part of Design No. 35,968, dated June 24, 1902.

Application filed April 28, 1902. Serial No. 105,121. Term of patent 3½ years.

To all whom it may concern:

Be it known that I, GEORGE H. TAYLOR, a citizen of the United States, residing in the borough of Manhattan, city, county, and State of New York, have invented and produced a new and useful Design for a Trimming, of which the following is a specification, reference being had to the accompanying drawings, wherein—

Figure 1 is a face view of a piece of fabric embodying my design, and Fig. 2 an edge view of the same looking from one side.

My new design consists in a trimming of the particular shape and ornamentation shown in the drawings, to wit:

A is a narrow plaited or ruffled band. Starting from the center B of said band A is a ribbon C, running in a zigzag course at right angles thereto and projecting on one side thereof, said ribbon C at the turning-points D being manipulated in such a manner as to produce the effect of a row of inclined bodies E, approximately triangular in shape, with the ruffled band A running parallel thereto and forming the basis of the upper sides of said bodies E.

I claim—

The design for a trimming substantially as shown and described.

GEORGE H. TAYLOR.
